(57) **CLAIM**

The ornamental design for a dandelion lamp, as shown and described.

DESCRIPTION

FIG. 1 is a perspective view of my dandelion lamp design. FIG. 2 is front elevation view thereof.

FIG. 3 is a right side elevation view thereof.

FIG. 4 is left side elevation view thereof.

FIG. 5 is a rear elevation view thereof.

FIG. 6 is a top plan view thereof.

FIG. 7 is a bottom plan view thereof.

FIG. 8 is a perspective view of the embodiment of FIG. 1, shown in the environment of a clear outer cover.

FIG. 9 is an enlarged detail view of the lamp head portion of the design.

FIG. 10 is an enlarged detail view of one dandelion seed element of the lamp head portion of my design; and, FIG. 11 is a cut-away view of the interior of the lamp head portion of my design.

The light bulb is omitted from the remaining figures for clarity of illustration.

The dashed lines showing the base and the clear cover are for illustrative purposes only and form no part of the claimed design.
